UNITED STATES PATENT OFFICE

CHARLES D. RODEBAUGH, OF WINSLOW, ILLINOIS.

SPRING-BED.

SPECIFICATION forming part of Letters Patent No. 279,188, dated June 12, 1883.

Application filed March 29, 1883. (No model.)

To all whom it may concern:

Be it known that I, CHARLES D. RODEBAUGH, a citizen of the United States, residing at Winslow, in the county of Stephenson and State of Illinois, have invented certain new and useful Improvements in Spring-Beds, of which the following is a specification, reference being had therein to the accompanying drawings.

Figure 1 is a top plan view of my spring-bed.

Fig. 2 is a longitudinal section with the head portion in an inclined position. Fig. 3 is a view of one of the springs and clamp. Fig. 4 is a view in perspective of the clamp detached.

A A are the outside longitudinal supporting bars, and A' A' are intermediate longitudinal bars. Upon these bars the springs are supported in such manner that a section, C, of them—say a third—may be set at any desired inclination to the other section, B, in order to support a part of the mattress at a greater height than the remainder of it.

D represents the cross-slats, carrying the springs belonging to the stationary section B. They rest upon the bars A A', to which they may be screwed or otherwise secured.

E represents the slats which carry the springs of the adjustable section C. They are supported upon and secured to longitudinal pieces F F F' F', which are preferably located above bars A A' A' A', respectively.

G G are links pivoted to pieces F' F' at f, at or near one end of said pieces, and pivoted at their other ends at a to bars A', the pivots a being located beneath the opposite ends of pieces F' F' from those which carry pivots f.

H H are levers pivoted to links G at points h, intermediate between pivots a and f, and having at their ends pins or friction-rollers a' f', which project laterally toward pieces A' F', and engage with longitudinal grooves a' f' in the faces thereof. A' F' are connecting and stiffening rods which join the ends of levers H. Their ends may be utilized as pins for engagement with grooves a' f', if desired.

It is evident that the adjustable spring-section C may be raised to any desired height within certain limits, and there secured by holding-links G and levers H in the position which they have assumed relative to one another by any suitable means. I prefer, however, to use ratchets I, attached to bars A' and dogs J on the lower ends of levers H. These

dogs may be operated simultaneously by means of a cross-piece, K, connected to them and extending to the side of the bed within convenient reach.

The relative heights to which the inner and outer edges of spring-section C will rise, and the consequent inclination which it will assume at various heights, depend upon the position of the pivots h.

I prefer to make the distances h a and h f in the proportion of about two to one, and the distances h' f' h' a' in about the same proportion, thus causing the section C to oscillate substantially about the dividing-line between it and section B. The oscillation of the adjustable section about this particular line of hinging is very advantageous. Since said line lies in the same horizontal plane with the top surfaces of the springs, said springs are not crowded together by the oscillation, as would be the case if the line of hinging were in the plane of bars A A', (the manner of construction heretofore employed;) but, on the contrary, a continuous taut surface is preserved throughout the oscillation, for the firm and elastic support of the mattress. Moreover, there is no danger of crumpling, rubbing, or wearing the under surface of the mattress, as would be the case if the springs of the adjustable section were crowded against those of the stationary section by the oscillation of the former.

The springs L are constructed of an inner coil, l, and outer coil, l', tapering downward, connected at the top by a horizontal portion, l'', and at the lower ends by a loop, l''. One of the coils terminates in a vertical portion, l'', for securing the spring in place. Preferably I construct the spring of one piece of wire, as shown, one end of it forming the loop l'', the other end the vertical part l'', and an intermediate portion the part l''. The part l'' is situated beneath the upper turn of one of the coils and transmits the pressure thereon to the other coil, both coils being thus effectually utilized.

The springs L are secured to the frame at suitable distances apart, and are united at their upper ends by clamps or links M, of peculiar construction. They are made of two pieces of spring-wire, having loops m at their middles, interlaced, as clearly shown in Fig. 3, and formed with hooks m' at their ends. Each clamp is thus enabled to connect four contiguous springs.

These clamps form a flexible and elastic connection between the springs L, the manner of interlacing the wires being such that the loops *m* will approach one another upon the application of any strain at the hooked ends, their approach being regulated by the friction of the wires upon one another, and their return to a normal position being insured by their elasticity. Each clamp is therefore a spring in itself, which permits the drawing apart of the hooked ends and retracts them when the pressure is removed. Moreover, these clamps present a broad supporting-surface to the bed between the springs, thus forming a practically continuous elastic surface.

I am aware that levers pivoted at one end to the spring-support and to the bed-frame, pivoted together at their middle, and having a sliding engagement at their other ends with the spring-support and bed-frame have been used to regulate the height of spring-beds as a whole, and I do not claim such construction, broadly, as my invention.

What I claim is—

- 25 1. A spring-bed having a stationary spring-section and adjustable spring-section oscillating substantially about the line of junction of the surfaces of the sections, and means for securing the adjustable section at various inclinations, substantially as set forth.
- 30 2. In a spring-bed, the combination of a stationary section, an adjustable spring-section oscillating substantially about the line of junction of the surfaces of the sections, devices which connect the tops of the springs along said line of juncture, and means for securing the adjustable section at various inclinations, substantially as set forth.
- 35 3. In a spring-bed, the combination, with a stationary spring-section, of an adjustable spring-section connected to the frame by oscillating links, levers pivoted to said links and bracing apart said section and frame, and means

for securing said levers in various positions, whereby the position of one portion of the surface of the bed may be changed relatively to the other portion, substantially as set forth. 45

4. In a spring-bed, the adjustable spring-section C, links G, pivoted to said section and to the main frame, levers pivoted to links G and 50 engaging by a sliding contact with the said section and bottom frame, and means for securing said levers in position, substantially as set forth.

5. In a spring-bed, the combination of the adjustable section C, links G, levers H, engaging with the longitudinal grooves *a*² *f*² in the section-supports and in the main frame, and dogs J, pivoted to said levers and engaging with the base-frame, substantially as set forth. 55

6. The combination, with the dogs J, which 60 secure the levers H in position, of means extending to the sides of the bed for connecting said dogs and operating them simultaneously, substantially as set forth.

7. The individual springs L, consisting of 65 two concentric coils connected at their tops, the lower end of one coil being adapted to be inserted vertically through the slat, and the lower end of the other forming the loop *l*³ and encircling the vertical portion, whereby the ends 70 are connected, and an annular collar formed for the support of the spring, substantially as set forth.

8. The herein-described clamp or connection M, consisting of two pieces of wire bent to form 75 loops *m*, and interlaced so that the two legs of each loop lie against opposite faces of the opposite loop, and interlock with one another at the center of said loop, substantially as set forth.

In testimony whereof I affix my signature in 80 presence of two witnesses.

CHARLES D. RODEBAUGH.
